(57) **CLAIM**

The ornamental design for an MRI head coil mirror assembly, as shown and described.

DESCRIPTION

FIG. 1 is a front perspective view of an MRI head coil mirror assembly showing our new design;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof;

FIG. 8 is a rear perspective view thereof; and,

FIG. 9 is an additional front perspective view thereof.

The broken line portion of the figures is included to show unclaimed subject matter only and forms no part of the claimed design.

The interior intersection of the mirrored panels does not form part of the claimed design.
